MAILBOX SUPPORT AND SIGN

Winford L. Enghauser, Cincinnati, Ohio

Application February 26, 1947, Serial No. 730,919

2 Claims. (Cl. 40—128)

1

This invention relates to outdoor signs and is particularly directed to an improved sign structure which may be used, for example, as the means for identifying the owners of mail boxes or for other uses where the sign is subjected to outdoor exposure. The present inventor has conceived of the present invention primarily for use in connection with the identification of mail boxes but it is not intended to limit the invention to such use for its general construction adapts it for use in sign structures for other uses.

It is well known that in the rural districts it is the common practice for the house owner to place his name and rural route box number on the mail box. In fact, in recent years the government has required that all mail boxes be properly marked in such manner that they may be readily identified by the mail carrier as he approaches by vehicle. The problem of maintaining printed identification has been considerable since the printing tends to fade out due to constant exposure to the elements. Thus, frequent renewal of the printing is necessary and there has been a great deal of difficulty in enforcing the rule as to clear, visible marking. In addition, since the sign on the mail box is the rural householder's means for directing persons to his or her home, it is highly desirable that the marking be clear and distinct and that it remain so for a long period of time.

Accordingly, it has been the principal objective of the present inventor to provide an identification sign for this use and any other related uses, which sign is permanent in character, readily visible and of extremely pleasing appearance.

It has been a further object of the present inventor to provide a sign structure of this character which is of extremely simple construction and which is readily assembled to display the desired information.

It has been a still further object of the present inventor to provide a structure of this character which will have the additional utility of properly supporting the mail box relative to its standard and which will be so located relative to the box as to satisfy the requirements for quick and ready identification of the box and which when thus assembled provides, with the mail box and support, an extremely artistic and pleasing appearance.

Other objects and certain advantages will be more fully apparent from the following description of the drawings in which:

Figure 1 is a side view of a mail box standard

2

showing the improved sign in position supporting the mail box on the standard.

Figure 2 is an end view of the upper portion of the standard illustrating the mail box and sign in end view.

Figure 3 is an enlarged fragmentary view taken from Figure 1 detailing the sign.

Figure 4 is a sectional view taken on line 4—4 of Figure 3.

Figure 5 is an exploded view taken similar to Figure 4 but displaying the parts in disassembled position.

Referring to the drawings, which disclose a preferred embodiment of the invention, the mail box stand is indicated generally at 10. It consists of a vertical standard 11 supporting a horizontal hanger bar 12. The hanger bar 12 as well as the vertical standard is formed of pipe, the horizontal hanger bar being of less diameter than the standard and being disposed through a bore 13 in the standard. This hanger bar projects a greater amount at one side of the standard than it does at the other, the portion which extends the greatest amount constituting the support bar upon which the mail box is supported.

The assembly standard and hanger bar are maintained in assembled relationship by means of a plurality of braces or gusset bars 14, preferably four, these bars being formed of pipe of small diameter. As indicated, the bars are attached to the standard 11 and hanger 12 by means of bolts and nuts indicated at 15 or they may be secured by means of welding if desired. The gusset bars are curved in order to embellish the appearance of the stand.

The mail box 20 is hung upon the hanger bar 12 by means of pairs of brackets 21, there being a pair at each end of the box. The respective brackets are secured to the hanger 12 and the mail box by means of screws 22. The ends of the brackets are arcuate whereby they fit the contour of the hanger bar at one end and the mail box at the other, providing in this respect attachment flanges 23.

The respective pairs of supporting brackets are spaced apart as indicated in Figure 4 and the identification plate generally indicated at 24 is supported in position between the members of the pairs between the hanger bar and mail box. The plate 24 consists of three general parts, namely a colored filler plate 25 which is formed of plastic or similar material and which may be of a luminescent nature if desired, and two perforated aluminum plates 26 disposed at the re-

spective opposite sides of the central plate. Also, horizontal frame strips 27 are provided along the respective upper and lower horizontal edges of the assembled sign.

As indicated in the exploded view the colored plate or filler element 25 is in the center. The entire assembly is held together and attached at its ends between the elements of the pairs of brackets 21 by means of the nuts and bolts generally indicated at 28 which pass through the support strips or brackets 21 at the respective corners of the sign.

As set forth, the colored central plate 25 may be made of plastic or any similar material. It may have luminescent qualities so as to catch the light from passing cars at night and thus may provide an easily readable sign which will function in darkness as well as in daylight. The outside plates 26, which may be of aluminum, are perforated or cut out to provide the letters 29 which will show up against the background of the central plate. Thus, when the sign is assembled, the only part of the colored filler visible is that which will show through the perforations (Figure 3).

It will be evident that this sign will be extremely durable. It will be impossible for the elements to wash off the identifying letters or numbers and the sign will far outlast normal printing. The contrast between the light colored aluminum and the dark background of the central plate makes the sign visible at great distances and when a luminescent material is used, the sign has great visibility at night. It is appreciated that the invention has many other uses apart from that in connection with a mail box and in the broader sense. The invention is concerned with the structure of the sign per se for any use. The specific application of the sign to mail box use provides additional features of invention which are set out in the preamble and in the claims.

Having described my invention, I claim:

1. A rural delivery mail box support assembly adapted to be secured to and depend from a horizontally disposed hanger bar comprising; a pair of support brackets disposed in spaced parallel relationship; each bracket including a pair of support strips having attachment flanges at the respective upper ends adapted to be secured to the hanger bar and attachment flanges at the respective lower ends configurated to conform to the contour of the top of a rural delivery mail box and adapted to be secured thereto; a rectangular

nameplate; the support strip of both pairs being spaced to embrace the respective ends of the name plate; said name plate being of laminated construction including a filler element disposed between two outer plate members, with the outer plate members being stenciled to expose the filler element in name wording; frame strips at the upper and lower edges of the respective outer plates; said support strips, frame strips and name plate having aligned bores therethrough at the four corners of the name plate; and fastening means extending through said bores and adapted to draw said support strips toward each other against said frame strips whereby the parts of the assembly are secured together as a unit.

2. A rural delivery mail box support assembly adapted to be secured to and depend from a horizontally disposed hanger bar comprising; a pair of support brackets disposed in spaced parallel relationship; each bracket including a pair of support strips having attachment flanges at the respective upper ends adapted to be secured to the hanger bar and attachment flanges at the respective lower ends configurated to conform to the contour of the top of a rural delivery mail box and adapted to be secured thereto; a rectangular nameplate; the support strip of both pairs being spaced to embrace the respective ends of the nameplate; said nameplate being of laminated construction including two stenciled outer plates and an intermediate plate; said rectangular nameplate having holes therethrough at each of the four corners; said support strips having holes therethrough in alignment with the holes in the nameplate and fastening means extending through each of the aligned holes for drawing the support strips of each bracket toward each other whereby the parts of the nameplate are clamped together and the support assembly is secured together as a unit.
